UNITED STATES PATENT OFFICE.

FREDERICK J. CLARK, OF BUFFALO, NEW YORK, ASSIGNOR TO EASTMAN MACHINE CO.,
OF BUFFALO, NEW YORK.

CLOTH-CUTTING MACHINE.

1,271,279.

Specification of Letters Patent.

Patented July 2, 1918.

Application filed December 14, 1916. Serial No. 137,044.

To all whom it may concern:

Be it known that I, FREDERICK J. CLARK, citizen of the United States, residing at Buffalo, in the county of Erie and State of New York, have invented a new and useful Improvement in Cloth-Cutting Machines, of which the following is a specification.

This invention relates to portable cloth cutting machines of the kind that are moved about by hand on a cutting table and have a base or base plate on which the knife and driving motor are mounted and which rests and is adapted to move on the table beneath a lay of cloth or other material to be cut. The cloth or material bears on and moves over the upper surface of the base past the knife in the use of the machine. Some kinds of material, such for example as friction fabric and insulating fabric, do not slide freely over the base on account of the nature of their surfaces, but cling to the surface of the base and thus materially hinder the easy and proper operation of the machine.

One of the objects of this invention is to overcome this difficulty by providing the base of the machine with rotatable rollers arranged so as to form rolling supports for the material which facilitate the movement of the material over the base and thus reduce the effort necessary to move the machine along. Another object of the invention is to provide improved securing means for the roller supports for the base.

In the accompanying drawings in which two different embodiments of the invention are shown:

Figure 1 is a perspective view on a reduced scale of a cloth cutting machine having one form of base embodying the invention.

Fig. 2 is a fragmentary plan view of the rear end of the machine base.

Fig. 3 is a bottom plan view of the base.

Fig. 4 is a perspective view detached of one of the securing plates for the supporting rollers.

Fig. 5 is a longitudinal sectional elevation of the base on line 5—5, Fig. 3.

Fig. 6 is an enlarged transverse sectional elevation thereof on line 6—6, Fig. 3.

Fig. 7 is a fragmentary bottom plan view thereof showing one pair of supporting rollers disconnected.

Fig. 8 is a bottom plan view on a reduced scale, of a base of modified construction,

An electric cloth cutting machine having a reciprocating knife 9 is illustrated in the drawings. With the exception of the improvements in the base, hereinafter described, the machine may be of any usual or suitable construction.

In the construction shown in Figs. 1-7, the base comprises a main central plate 10 to which the motor supporting standard 11 is secured, and a surrounding edge plate 12 which slopes downwardly from the edges of the central plate 10 and has a thin outer edge adapting it to readily pass under the material. The central plate is supported on yieldingly mounted wheels or rollers 13 to reduce the vibration and is thus adapted to move up and down relative to the edge plate so that the latter can lie stationary flat upon the table. Suitable springs 14 connecting the edge plate and the central plate press the former lightly down upon the table. This is a well known construction of base.

15 and 16 represent rotatably mounted rollers extending transversely of the base in front and in rear of the knife standard and adapted to provide rolling supports for the material being cut. In the base shown in Figs. 1-7, which has the surrounding edge plate 12, these rollers are preferably arranged at the front and rear edges of the central plate 10 and extend substantially from side to side thereof in openings 17 of the base and project slightly above the top surfaces of the base plates 10 and 12, so as to hold the material from contact with the base plates in the vicinity of the rollers. The rollers are preferably journaled in bearing pieces 18 which are secured to the underside of the central plate 10 and project into the openings provided therefor in the edge plate 12. The rollers rest loosely and are adapted to turn in seats 19 in the bearing pieces which are suitably shaped to prevent the displacement of the rollers, the open sides of the bearing seats being for instance, narrower than the diameter of the parts of the rollers seated therein so that the rollers cannot be lifted out of the seats.

The base shown in Fig. 8 does not have a surrounding edge plate as above described, but has instead a movable lifting or edge plate 20 with a sloping upper surface and thin edge located at the front end only of a main base plate 21, which has beveled or downwardly sloping side and rear edges, 110

The lifting plate 20 can be connected to the main base plate in any suitable way, as for instance by spring strips 22.

In this construction the front roller 15 is located at the front edge of the main plate in the opening in the lifting plate 20, and the rear roller 16 is located in an opening 23 in the main plate at the rear end of the flat portion of the upper surface of this plate. 10 The rollers can be journaled, as before explained, in seats in bearing pieces 24, 25 secured to the underside of the main base plate.

In both constructions the rollers act in 15 the same way to hold the material out of contact with the adjacent portions of the surface of the base and form rolling supports for the material.

The supporting rollers or wheels 13 for 20 the machine are arranged as usual in pairs journaled in any suitable way on the opposite ends of flat springs or spring strips 26 which extend lengthwise under the base at the side portions thereof and are attached 25 between their ends to the underside of the main base plate.

Each of these springs 26 is preferably secured between its ends in a seat or recess 27 in a downwardly projecting lug or thickened part 28 of the main base plate, this lug or part having a lip 29 which extends inwardly under one edge of the spring, see Figs. 3 and 6. A plate 30 fastened to the underside of the base plate by a screw 31 or otherwise and extending under the opposite edge of the spring cooperates with the lip 29 in retaining the spring in the seat 27.

The seat 27 is made enough wider than the spring to permit the latter to be moved 40 laterally in the seat to disengage it from the lip, and in order to prevent such movement and hold the spring in engagement with the lip, the plate 30 is provided with one or more tongues or projections 32 which 45 extend upwardly between the side of the seat and the adjacent edge of the spring. The spring can be readily disengaged from the lip and detached when the plate 30 is removed. By means of this construction 50 the wheel carrying spring is securely fastened in place with a single screw. The main base plate is of course recessed or shaped to provide room over the wheels 13 to allow the wheels to yield upwardly.

55 Since the base is thus provided on its underside with supporting rollers or wheels adapted to roll on the table and on its upper side with rollers 15 and 16 adapted to roll against the underside of the overlying material, the machine can be easily operated for cutting a heavy lay of material which would not slide freely over the ordinary base.

I claim as my invention:—

65 1. A portable cloth cutting machine hav-

ing a base adapted to rest and move on a supporting surface beneath the material being cut and provided with rollers arranged to contact with the under side of the material and form rolling supports therefor to 70 reduce the friction between said base and said material.

2. A portable cloth cutting machine having a base adapted to rest and move on a supporting surface beneath the material being cut and provided with transversely extending rollers rotatably mounted thereon in front and in rear of the knife and arranged to contact with the under side of the material and form rolling supports 80 therefor to reduce the friction between said base and said material.

3. A cloth cutting machine having a base adapted to move beneath the material being cut and having rollers on its under and 85 upper sides, the rollers on said under side being arranged to roll on a supporting surface, said rollers on said upper side being arranged to contact with the under side of the material to reduce the friction between 90 said base and said material and said under and upper rollers acting together to permit said base to easily move between said material and the supporting surface.

4. A cloth cutting machine having a base 95 adapted to rest and move on a supporting surface beneath the material being cut and having downwardly sloping front and rear portions, and transversely extending rollers rotatably mounted on the base adjacent the 100 upper edges of said front and rear sloping portions and forming rolling supports for the material to reduce the friction between said base and said material.

5. A portable cloth cutting machine having a base adapted to rest and move on a supporting surface beneath the material being cut and comprising a main base plate and a movable edge plate, and transversely extending rollers rotatably mounted on said 110 main base plate and arranged to contact with the under side of the material and form rolling supports therefor to reduce the friction between said base and said material.

6. A cloth cutting machine having a base 115 adapted to rest and move on a supporting surface beneath the material being cut and comprising a main base plate and a movable edge plate surrounding the main base plate, and transversely extending rollers rotatably mounted on said main base plate at the front and rear edges thereof and arranged to contact with the under side of the material to form rolling supports therefor to reduce the friction between said base and said material.

7. A portable cloth cutting machine having a base adapted to rest and move on a supporting surface beneath the material being cut, transverse rollers supported by said 130

- base out of contact with said supporting surface and extending across a substantial portion of the width of said base and arranged to contact with the under surface of the material being cut and to be revolved by such contact with the material in the direction of movement of the material relative to the base to form rolling supports for the material.
- 10 8. A cloth cutting machine having a base adapted to move beneath the material being cut, supporting rollers for said base, spring strips on which said rollers are journaled, said base having a recessed seat for each of
- 15 said spring strips provided with a lip engaging one edge of the spring strip, and a securing plate which engages the opposite edge of the spring strip and has a projection extending between the last mentioned edge of the spring strip and the adjacent side of 20 the seat.
- Witness my hand this 12th day of December, 1916.

FREDERICK J. CLARK.
